UNITED STATES PATENT OFFICE.

EDWARD GILBERT, OF FREEPORT, ILLINOIS.

DESIGN FOR A SIGN.

45,931.

Specification for Design. Patented June 16, 1914.

Application filed October 25, 1913. Serial No. 797,349. Term of patent 7 years.

To all whom it may concern:

Be it known that I, EDWARD GILBERT, a citizen of the United States, residing at Freeport, in the county of Stephenson and State of Illinois, have invented a new, original, and ornamental Design for a Sign, of which the following is a specification, reference being had to the accompanying drawing, forming a part thereof.

The figure is a perspective view of a sign showing my new design.

I claim:

The ornamental design for a sign, as shown,

EDWARD GILBERT.

In the presence of:

R. J. CARNAHAN,

I. M. STEWART.
